UNITED STATES PATENT OFFICE.

LOUIS LEWIS, OF LONDON, ENGLAND.

STENCIL-PRODUCING PLATE.

1,286,363.

Specification of Letters Patent.

Patented Dec. 3, 1918.

Application filed June 3, 1915. Serial No. 31,979.

To all whom it may concern:

Be it known that I, LOUIS LEWIS, a subject of His Majesty the King of England, residing at London, England, have invented 5 certain new and useful Improvements in Stencil-Producing Plates, of which the following is a specification.

This invention deals with the production and use of printing stencils after the manner of the Zuccato perforating method in which prepared paper such as thin fibrous paper sheets coated with paraffin wax, or thin metallic sheets such as tin foil, are laid on a fine file-like plate or surface of hardened steel and subjected to pressure from a hardened steel point or style or type, the teeth of the file, wherever the pen or type exerts pressure, perforating the paper or the like, or causing the paraffin wax of the 20 waxed paper to spread, to produce a porous outline in the shape of the impressed letter or character or drawing through which the ink may pass in printing trypographically.

The chief object of the present invention 25 is to enable trypographic stencils to be made by tracing.

To this end according to this invention a stencil producing plate or surface of wire-fabric is used as the stencil-perforating medium; this plate or surface being supported by a transparent rigid backing having behind or under it a source of light. Thus the original to be copied by tracing, being supported under the stencil-perforating medium, preferably against that face of the transparent backing with aspect away from the stencil-perforating medium, as by means of a covering transparent plate, and a sheet of transparent or semi-transparent stencil material being placed over the stencil-producing medium, the making of a trypographic stencil copy of the original direct by tracing is accomplishable with good result by any ordinary person. As the stencil material the waxed paper known as "prepared cyclostyle paper" will be found quite suitable.

Further according to a preferred embodiment of the present invention and to better 50 realize the chief object thereof the coöperating elements viz., the stencil-producing medium and the transparent rigid backing are constituted in combination as a unit in which the component elements by direct or 55 indirect intercontrol are relatively bodily

immovable or at least relatively bodily immovable in their own plane.

For the purpose of maintaining the wire-fabric stencil-producing medium during the effective life thereof in proper condition as 60 an operating surface, this, under the present invention is furnished with a sustaining surrounding border or surrounding marginal rim of the requisite rigidity, such as a wooden or metal frame. Thus the whole 65 area of the perforating medium becomes equally available for tracing when so used, while by giving such surrounding rigid rim or border sufficient depth to form a stop or positioning rim or alternatively by furnishing such rim with local stops or positioning pins, the sustaining border or rim can be used to also position and hold the stencil producing surface in relation to its rigid backing, whether this be of transparent or 70 opaque material; this part of the present invention, viz., a wire-fabric stencil-producing sheet or surface having a sustaining border or both a sustaining and positioning border or margin is not confined only to 75 cases of producing trypographic stencils by tracing.

Preferably the component parts of the tracing unit are separably combined, and conveniently the unit is detachably held in 80 a suitable holder whereby the holding means may also serve to retain the stencil material in position while copying thereon from the original.

The size of the mesh of the wire-fabric 90 may vary according to the fineness or coarseness of the printing desired but it must not be so open as to allow the point or style or type to lacerate or unduly stress the material of which the stencil is made, by driving or 95 forcing it down into or at the interstices of the fabric. Thus the wire-fabric must be of such a mesh in relation to the impression element, that a succession of more or less fine holes are produced in the paraffin-paper 100 or its equivalent when writing or typing thereon while placed on the wire-fabric.

In a form of the invention found to work well a fabric of woven copper wire having 200 strands to the linear inch was used 105 and a sheet of this was fitted to a transparent backing plate and clamped at the edges by a surrounding frame, or tightening frame, comparable to the rim of a drum or tambourine. The backing plate 110

used for this purpose may conveniently be of glass.

Thus in the drawings:

Figure 1 is a plan view.

5 Fig. 2 is an elevation, and

Fig. 3 a sectional elevation of one constructional form of device under the invention for stencil making after the Zuccato method, by tracing.

10 Fig. 4 illustrates a fragment of a wire-fabric stencil-producing surface.

a designates a dual supporting and light frame or part light frame formed with a ledge b on which a removable supporting frame c is received with a fairly close fit. The tracing unit comprises a frame d having rounded off or beveled outer upper edges and a frame i between which, the margin of a wire-fabric sheet f is gripped.

20 The clamping frames d and i form both a sustaining and positioning border or margin for the wire-fabric which in itself is too flexible to be self supporting as an effective stencil-producing medium.

25 By appropriate dimensioning of the frame d and the transparent backing l, the inner faces of the frame form a detachable mount or frame for receiving the backing and for holding this so that by the direct intercontrol thereby created there can be no substantial relative bodily displacement of the frame and the backing.

In order to protect the original drawing n or the like from injury during copying 35 it is convenient and indeed preferred to secure this against the under face of the backing l by a transparent cover plate m, the backing thereby virtually becoming a dyad of superposed plates which, as shown, form 40 one element of the tracing-unit; the respective elements being under direct intercontrol as regards any relative bodily displacement as aforesaid.

As depicted, the tracing-unit is in part

supported by the top edge of the light or 45 part light frame a and in part by the upper face of the removable frame c. And in order to fasten the unit in relation to the frames a and c, a holding frame h having an interior horizontal marginal ledge e is 50 provided to fit over the tracing-unit and secure this against movement in any direction in relation to the frame c, when clips or other suitable fastenings j carried by the latter are engaged with the frame h. Under 55 the glass there will be a suitable source of light which may be either reflected day or artificial light or direct artificial light or any combination thereof.

Having placed the drawing or the like 60 to be copied between the superposed plates of the backing, the wire-fabric sheet is fitted over the backing, a sheet of stencil material g is placed over the wire-fabric and the whole fixed by the holding frame h, the 65 margin of the stencil sheet being gripped between the frames i and h. A stencil copy of the original may then be produced by a stylus without difficulty.

What I claim and desire to secure by Letters Patent is:—

In a stencil producing apparatus, a supporting frame provided with a ledge located below the top of the frame, a removable frame comprising a plurality of parts resting on said ledge, two transparent plates resting on said supporting frame and removably clamped to said removable frame, a translucent original to be copied held between said plates, a sheet of wire cloth 80 stretched over the upper transparent plate and means for securing the parts of the removable frame together to clamp the cloth and transparent plates therein.

Signed at London, England.

85 In testimony whereof I affix my signature.

LOUIS LEWIS.
